UNITED STATES PATENT OFFICE

JOHN H. RICHARDSON, OF MELROSE, AND LEROY W. ROLLINS, OF MEDFORD, MASSACHUSETTS, ASSIGNORS TO UNITED SHOE MACHINERY CORPORATION, OF PATERSON, NEW JERSEY, A CORPORATION OF NEW JERSEY

MANUFACTURE OF SHOES

Application filed May 23, 1927. Serial No. 193,675.

This invention relates to the manufacture of shoes and more particularly to the production of shoes the bottoms of which are characterized by great flexibility.

bending upwardly away from the adjacent face of the sole, in response to the pull of the upper, so that the shapeliness of the shoe imparted to it in lasting is permanently retained.

5 In the manufacture of certain kinds of shoes of the type in which the outsole is attached directly to the margin of the upper overlying the insole, for example by through-and-through fastenings such as stitches, an 55 insole of extreme longitudinal flexibility especially at the ball line is required, and yet of such a character that, while inexpensive to make and convenient to use, it will assist in maintaining the shape of the shoe 60 10 during wear and afford adequate anchorage for the fastenings which hold the upper in lasted position as well as for the through-and-through stitches by which the outsole, upper and insole are held together. Objects of this 65 15 invention are to provide improvements in shoe manufacture with particular reference to these requirements.

To this end the invention, in one aspect, provides a novel insole comprising a thin, 70 20 flexible base member and a relatively stiff strip of material secured to the margin of the base member. The strip is preferably composed of fibrous material to afford 75 strength and non-fibrous, amorphous material to provide stiffness. As illustrated, the strip is composed of a layer of non-fibrous, 80 30 resilient material such as sheet celluloid and a fibrous material such as canvas. The canvas preferably forms the outer layer and has its inner face friction coated to adhere to the celluloid. The base member is of relatively thin material but has sufficient strength laterally to resist the outward pull of the lasted upper. The fibre strip stiffened with cellulosic 85 40 material, which preferably extends from the breast line along the shank and around the forepart to the breast line again, opposes sufficient resistance to the strain of the lasting fastenings so that the tension on the upper is retained until the outsole is applied. 90 45 When the shoe is worn the shape of the last is retained because the strip, with the other portions of the shoe bottom, is made to correspond accurately to the shape of the last bottom and has sufficient rigidity against

95 50 Referring to the drawings,— In other aspects the invention provides a novel method of shoe manufacture including the use of an insole stiffened at its margin by cellulosic material, for example, in the manner herein set forth, and also a novel shoe having such an insole incorporated therein.

Fig. 1 is a perspective view of the completed insole showing the lower surface; Fig. 2 is an exploded view, in perspective,

showing the parts which make up the insole;

Fig. 3 is a perspective view, partly in section, showing the insole upon a last and the upper being lasted and secured to it; and

5 Fig. 4 is a fragmentary sectional view of the completed shoe.

Referring to Fig. 2 of the drawings, it

10 will be seen that the first layer of the insole consists of a base layer 10 having the shape of a complete insole. This layer preferably consists of Canton or cotton flannel fabric, the fleece side being next to the last bottom and the outer side being covered with a rubber or gutta percha composition such as is

15 used in the manufacture of friction-coated fabric. About the shank and forepart of this first layer 10 is sewed a lasting lip comprising a composite strip of material made up of a layer 12 of sheet celluloid or other non-fi-

20 brous, resilient material and a layer 14 of friction-coated canvas. The strips of celluloid and canvas are first died out in approximately the required shape and are caused to adhere together by reason of the friction coating.

25 The composite strip is then applied in a substantially undistorted condition to the base member or layer and the outer edge of the composite strip is sewed by a seam 16 to the edge of the layer 10 and extends about the shank and forepart of the sole from breast

30 line to breast line, forming a lip to which the upper may be secured. Under the strip 12, 14, from the ball line forwardly, a filler 18 is inserted, this filler consisting preferably of

35 a properly shaped piece of felt having the margins which extend under the strip skived off. A shank piece 20 extends from the heel-seat to the ball line, this piece being preferably made of material such as leather-board

40 or fibreboard, the rear portion covering the heel-seat and the shank portion being reduced in width so as to fit between the seams 16 holding the shank portions of the strip 12, 14. A metal shank stiffener 22 may be se-

45 cured to the shank piece 20. In order to secure in the insole the shape and effect of a molded insole, the shank stiffener is given the required longitudinal curvature so that when secured to the shank piece the shank piece

50 will be given the proper shape, which shape will be imparted to the insole when the shank piece and stiffener are secured to it. At the heel-seat a piece 24 of friction-coated canvas is secured to the shank piece 20, this piece 24 being preferably of a thickness approxi-

55 mately equal to that of the composite strip 12, 14.

In the use of this insole, as illustrated, in its application to the manufacture of McKay 60 sewed shoes, it is applied to the bottom of a last 26 as usual and an upper 28 is assembled thereon. The shoe may be pulled over as usual and the heel and toe lasted upon a bed machine, the upper at the heel-seat being

65 wiped in and fastened by tacks extending

through the various layers of the insole at the heel-seat. At the toe the upper is wiped in and tacked to the strip 12, 14. About the toe portion the strip 12, 14 affords a firm outline corresponding to that of the last over 70 which the upper may be wiped and which will maintain the shape of the upper during the wear of the shoe. At the sides the upper may be lasted in any usual manner. Preferably, however, a lasting and stapling machine such as that disclosed in United States Letters Patent No. 1,731,855, granted October 15, 1929, on application of George Goddu, is employed. In the use of this machine the upper will be tightly lasted by a 75 gripper 30, and, while control the upper 28 is maintained by a staple nozzle 32 and the gripper 30, a staple 34 will be inserted through the upper and composite strip 12, 14 and clenched by a channel guide and anvil 36 upon 80 the under side of the strip. An outsole 38 is then laid and the outsole, upper, composite strip and the underlying layers 10, 18 are secured together by through-and-through stitching 40, as is usual in the manufacture of 85 shoes of the McKay type. These stitches will sink into the soft fleece surface of the base layer 10 and may be covered by a slip-sole 42; the nap surface and felt filler forming a cushion for the forepart of the foot. 90

The resulting shoe has an extremely flexible forepart, a sufficiently stiff shank portion molded to the longitudinal curve of the shank, and enough substance or material at the heel-seat portion to hold the lasting tacks, heel-seat nails and heel nails. At the same time the strip 12, 14 serves, because of its stiffness against bending about an axis extending in the direction of its length and because its edge corresponds to the shape of the last, to 105 hold in place the part of the upper extending from the edge of the last to the seam and hence maintains the shape of the insole and the overlasted upper in correspondence with the shape of the last, not only during the 110 process of manufacture, but also afterward, with the result that the trim contour and shapeliness of the shoe are retained during wear. Furthermore, the composite strip is sufficiently rigid against bending its own 115 plane, being supported by the base layer 10, to prevent loss of tension of the lasted upper which is stapled to it, and its thickness, together with other portions of the insole, affords firm hold for the through-and-through 120 stitches which secure the insole, upper and outsole together. At the same time the insole is extremely flexible to bending in the longitudinal median plane of the shoe, that is, in the direction in which it is bent when worn. 125

Having thus described our invention, what we claim as new and desire to secure by Letters Patent of the United States is:

1. An insole comprising a fabric base having its outer face friction-coated, a felt filler 130

covering the forepart of the base, and a fibre shank piece covering the shank and rear part.

2. An insole comprising a fabric base having its outer face friction-coated, a felt filler covering the forepart of the base, a fibre shank piece covering the shank and rear part, and a lasting strip secured to the base at the outer edges of the base and strip.

3. An insole comprising a base layer and a two-ply flat strip comprising a canvas layer and a celluloid layer, said strip being narrower than the base layer and secured to the margin thereof.

4. An insole comprising a base layer and a narrow strip of celluloid secured to said base about its periphery and forming a stiff lip to which the upper may be secured in lasting.

5. An insole comprising a fabric base having a friction-coated outer surface, a forepart filler, a shank piece frictioned to said base, and a lip to which the upper is to be secured in lasting formed by a stiff strip sewed to the margin of the base.

6. An insole comprising a fabric base covering the bottom of the last, a fibre layer covering the shank and heel-seat, and a fabric layer covering the heel-seat of the fibre layer, the fabric layer being frictioned to the fibre layer.

7. A composite insole comprising a thin and flexible base layer and a relatively stiff strip attached to the base layer along the outer margins of the shank and forepart of the base and at the outer edge of the strip, the strip being free from the base layer inwardly of its outer edge and terminating at the breast line.

8. A composite insole comprising a thin and flexible base layer, a relatively stiff strip attached to the base layer along the outer margins of the shank and forepart of the base and strip, the strip being free from the base layer inwardly of its edge and terminating at the breast line, and a stiffener for the shank and heel-seat the shank portion of which lies beneath the attached strip.

9. An insole for use in shoes of the McKay type comprising a base layer to engage a last bottom, and a strip, to which the upper is to be secured in lasting, attached to the base layer, said strip being stiffened with celluloid.

10. An insole for shoes having a stiff marginal portion formed of a separate piece of undistorted sheet material and a flexible interior portion, said marginal portion being adapted when secured with the upper to an outsole to hold the upper against the outsole and to maintain the peripheral shape imparted to the upper in the lasting operation.

11. An insole for shoes having a marginal portion formed of a separate piece of undistorted sheet material sufficiently stiff to prevent displacement of the over-lasting portion

of the upper heightwise of the shoe, and a flexible interior portion, the insole as a whole being flexible longitudinally of the shoe.

12. An insole comprising a base member and a strip of material which is stiff relatively to the base member secured to the base member along a line adjacent to the outer edges of the base member and the strip, said strip comprising a layer of fibrous material and a layer of non-fibrous material secured together.

13. A composite insole comprising a thin and flexible base layer and a strip stiffer than the base layer attached to the base layer along the outer margins of the forepart of the base and strip, the strip being free from the base layer inwardly of its edges and comprising separate layers secured together.

14. A flexible, ribless, fabric insole marginally reinforced by attachment thereto of a separate piece of non-fibrous material.

15. A flexible, ribless insole for attachment to an upper and outsole by through-and-through stitches having on its marginal portions only a stiff strip comprising fibrous material and cellulosic material.

16. A flexible fabric insole having its margin only stiffened with sheet celluloid.

17. A flexible insole comprising a base layer and a marginally applied flat strip of resilient non-fibrous material having a smooth, uninterrupted outer surface and a fabric inner surface.

18. An insole for McKay shoes comprising a layer of flexible material and a marginal strip secured thereto, said strip being stiff relatively to said layer and adapted to withstand the upward pull of the upper on the edge of the insole during wear and penetrable by the needle of a machine for sewing through-and-through stitches.

19. A flexible insole having its margin only stiffened with a strip composed of fibrous material and non-fibrous cellulosic material.

20. An insole to which an upper and an outsole are to be attached by through-and-through stitches having on its outer face a thickened marginal edge for receiving the upper securing fastenings and on its inner face a soft nap surface in which the through-and-through stitches may be embedded.

21. A lasted shoe comprising an insole provided with a lip stiffened by amorphous cellulosic material, and an upper fastened in lasted relation to the lip by metallic fastenings.

22. A lasted shoe comprising an insole provided with a lip stiffened by non-fibrous cellulosic material and an upper fastened in lasted relation to the lip by staples clenched on the lip.

23. A shoe comprising an insole having a layer of non-fibrous cellulosic material upon its margin, an upper overlying the cellulosic

material, and an outsole secured to the overlying portion of the upper and the insole by through-and-through stitches.

24. A shoe comprising an insole having upon its marginal portion celluloid stiffening material, an upper overlying the celluloid stiffening material and secured to the insole by permanent metallic fastenings so driven as not to penetrate through the insole, and an outsole secured to the overlying portion of the upper.

25. A shoe comprising an insole having upon its marginal portion celluloid stiffening material, an upper overlying the celluloid stiffening material and secured to the insole by staples passing through the upper and the celluloid stiffening material, an outsole engaging the overlying portion of the upper, and stitches securing the outsole, upper, celluloid stiffening material and insole together.

26. A shoe comprising an insole having upon its marginal portion a lip including celluloid stiffening material, an upper secured to the lip by staples passing through the upper and the lip, an outsole engaging the upper, and stitches securing the outsole, lip, celluloid stiffening material and insole together.

27. That improvement in methods of making shoes which consists in providing upon a last an upper and an insole having on its marginal portion non-fibrous cellulosic material, lasting the upper over upon the cellulosic material, securing the upper in lasted position by staples, and thereafter applying an outsole and securing it to the shoe.

28. That improvement in methods of making shoes which consists in providing upon a last an upper and an insole having non-fibrous cellulosic material upon its marginal portion, lasting the upper over upon the cellulosic material, securing the upper in lasted position by staples driven through the upper and cellulosic material, and then applying and securing an outsole in any usual manner.

29. That improvement in methods of making shoes which consists in providing upon a last an upper and an insole, said insole being provided on its marginal portion only with celluloid stiffening material, lasting the upper over upon the celluloid stiffening material, securing the upper in lasted position by staples, and securing an outsole to the overlasted upper.

30. That improvement in methods of making shoes which consists in providing upon a last an upper and an insole having non-fibrous cellulosic material upon its marginal portion, lasting the upper over upon the cellulosic material, securing the upper by staples to the insole, applying an outsole to the shoe, and attaching the outsole by through-and-through stitches passing

through the outsole, upper, cellulosic material and insole.

31. That improvement in methods of making shoes which consists in providing upon a last an upper and an insole having non-fibrous cellulosic material upon its marginal portion, lasting the upper over upon the cellulosic material, applying an outsole to the shoe, and attaching the outsole by through-and-through stitches passing through the outsole, upper, cellulosic material and insole. 75

32. That improvement in methods of making shoes which consists in providing upon a last an upper and an insole having non-fibrous cellulosic material upon its marginal portion, lasting the upper over upon the cellulosic material, securing the upper by metallic fastenings so driven as not to penetrate through the insole, applying an outsole to the shoe, and attaching the outsole by through-and-through stitches passing through the outsole, upper, cellulosic material and insole. 80

In testimony whereof we have signed our names to this specification.
